ANTIRATTLE SPRING DEVICE

Filed March 12, 1928

Inventor

H.E. Blomgren.

By his Attorney

UNITED STATES PATENT OFFICE

HENRY E. BLOMGEN, OF BROOKLYN, NEW YORK

ANTIRATTLE SPRING DEVICE

Application filed March 12, 1928. Serial No. 261,072.

This invention has reference to the spring end connections of a motor vehicle, where the spring is connected with the body or frame, and is provided with some form of a hinge 5 joint, and particularly relates to what is known as a shackle joint where the usual sleeves are connected by side links that swing to permit flexing of the spring.

It is an object of the invention to provide 10 a resilient block that can be applied to the shackle without removal or even loosening of the shackle bolt or bolts, and which will insure considerable pressure against the sleeves and also against the side links of the shackle.

15 In the accompanying drawings showing embodiments of my invention—

Figure 1 is a side elevation of the device in use.

Fig. 2 is an end view of the same parts. 20 Fig. 3 is a cross section on the line 3—3 of Fig. 2.

Fig. 4 is a cross section of the line 4—4 of Fig. 1.

Fig. 5 shows the relative positions of the 25 parts before use.

Fig. 6 shows the insertion of the complementary block sections.

Fig. 7 shows one of the securing plates.

As shown the frame 2 is provided with the 30 usual sleeve end portion 3, that carries the pivot bolt 4. The spring 5 is provided with an eye 6, at the end engaged by the pivot bolt 7. These bolts are connected by links 8 and 9, which constitute the usual shackle 35 support for the spring that permits the end of the spring to move back and forth as the spring is flexed.

To prevent rattle and lost movement at 40 these hinge portions, I provide a block of resilient non-metallic material such as rubber, in two complementary portions or sections, adapted to be clamped together by a transverse member in the rectangular opening between the opposed links and the opposed eyes.

45 As shown I provide a rubber block formed of two complementary sections 10 and 11, that are similar and are brought together on their inner faces 12 and 13, as shown, in which position they form a rounded groove 14 by

and a similar rounded groove 15 on the upper side, by cut away portions in each section; and which grooves correspond to the eyes 3 and 6. It will be understood that these two complementary sections can be inserted from 55 opposite sides into the rectangular opening between the opposed links and the opposed eyes, as indicated in Figs. 3 and 4.

These blocks are provided with registering holes 16, 17, through which a bolt 18, with 60 nut 1, is passed, that will serve to draw the blocks together at the meeting faces 12 and 13; the blocks being inserted from opposite sides, as indicated in Fig. 5, that will bring the grooved ends 14 and 15 to engage the eyes 65 3 and 6, see Fig. 3. Clamping plates 19 and 20, are placed on the bolt 18, at holes in the plates, to press the sections inwardly; and as shown the block sections 10 and 11 are provided with extensions 22, 23, on the outer faces 70 around the bolt holes, that are somewhat conical in form. This will cause the plates 19, 20, to first engage the sections at the middle parts and will cause compression, that will result in outward distension of the side 75 walls of the sections, that will thus be pressed against the links and the eyes of the shackle.

Means are further provided to cause the side walls of the composite block to be pressed against the side links 8 and 9, as the sections 80 are drawn together by the bolt 18; and as shown the side walls 24 and 25 on one side of the composite block are inclined inwardly to the meeting faces of the sections, to form a kind of channel; and at the opposite side 85 of the block, the walls 26 and 27 of the two sections are similarly inclined inwardly to the meeting faces of the sections, and form a channel. The distance apart of these opposed walls of the sections that are inclined, 90 is formed slightly greater than the distance apart of the opposed links of the shackle joint, as indicated in Fig. 6, so that when the sections are initially applied to the shackle from opposite sides, these inclined walls will 95 at once engage the inner walls of the links 9 and 8, and as the bolt causes approach of the sections, obviously the sections will be compressed against the links, as indicated in Fig. 4, the inclined walls acting as a wedge. 100

This will produce a strong outward pressure on the links, and prevent any possible rattle at such joints.

The pressure on the plates 19 and 20, by drawing up of the bolt 18 by its nut 1, will, by the flattening on the conical faces of the sections, cause outward distension of the sections at all of the side edges, and insure considerable pressure on the eyes 14 and 15 by the block sections; and the edge portions of the clamping plates will press inwardly on the sections at the edges and hold them in engagement with the eyes throughout the curved surfaces; which will produce friction between the block and sleeves or eyes as the shackle swings when the spring flexes, and will function as a snubber or shock absorber.

This invention is an improvement on the structure set forth in U. S. Patent No. 1,139,136 granted to me; also that set forth in patent granted to me October 23, 1928, No. 1,688,682.

What I claim is:—

1. The combination with a spring shackle formed of side links that connect and support upper and lower sleeve members by bolts, of a composite block of rubber compressed between said two pairs of opposed members on its four outer walls respectively, the block being formed of two complemental sections in engagement on the plane of the sleeve bolts, the composite block being provided with a channel on each of two opposite sides to engage said sleeve respectively, the other two opposite side walls of the composite block being inclined inwardly to the meeting faces of the sections to form a channel for engagement with the side links respectively, the composite block having a central transverse aperture, and a bolt projecting through said aperture to draw the sections together under compression against the said four engaged walls of the shackle.

2. The combination with a spring shackle formed on side links that connect and support upper and lower sleeve members by bolts, of a composite block of rubber compressed between said two pairs of opposed members on its four outer walls respectively, the block being formed of two complemental sections in engagement on the plane of the sleeve bolts, the composite block being provided with a channel on each of two opposite sides to engage said sleeves respectively, the other two opposite side walls of the composite block being inclined inwardly to the meeting faces of the sections to form a channel for engagement with the side links respectively, the composite block having a central transverse aperture, a bolt projecting through said aperture to draw the sections together under compression against the said four engaged walls of the shackle, said block inclined faces as formed being spaced apart a greater distance than the distance apart of the links, said sections being extended outwardly around the bolt, and an apertured plate on the bolt at each end portion that is pressed against said extensions to compress the block sections against all said engaged members of the shackle.

insertion of the sections from opposite sides of the shackle and drawing up of the bolt will cause said inclined faces to be considerably compressed against the links.

3. The combination with a spring shackle formed of side links that connect and support upper and lower sleeve members by bolts, of a composite block of rubber compressed between said two pairs of opposed members on its four outer walls respectively, the block being formed of two complemental sections in engagement on the plane of the sleeve bolts, the composite block being provided with a channel on each of two opposite sides to engage said sleeves respectively, the other two opposite side walls of the composite block being inclined inwardly to the meeting faces of the sections to form a channel for engagement with the side links respectively, the composite block having a central transverse aperture, a bolt projecting through said aperture to draw the sections together under compression against the said four engaged walls of the shackle, said sections being extended outwardly around the bolt, and an apertured plate on the bolt at each end that is pressed against said extensions to compress the block sections against all said engaged members.

4. The combination with a spring shackle formed of side links that connect and support upper and lower sleeve members by bolts, of a composite block of rubber compressed between said two pairs of opposed members on its four outer walls respectively, the block being formed of two complemental sections in engagement on the plane of the sleeve bolts, the composite block being provided with a channel on each of two opposite sides to engage said sleeves respectively, the other two opposite side walls of the composite block being inclined inwardly to the meeting faces of the sections to form a channel for engagement with the side links respectively, the composite block having a central transverse aperture, a bolt projecting through said aperture to draw the sections together under compression against all engaged walls of the shackle, said block inclined faces being spaced apart a greater distance than the distance apart of the links, said sections being extended outwardly around the bolt, and an apertured plate on the bolt at each end portion that is pressed against said extensions to compress the block sections against all said engaged members of the shackle.

5. The combination with a spring shackle formed of side links that connect and support upper and lower sleeve members by bolts, of a composite block of rubber compressed between said two pairs of opposed members on its four outer walls respectively, the block being formed of two complemental sections in engagement on the plane of the sleeve bolts, the composite block being pro-

vided with a channel on each of two opposite sides to engage said sleeves respectively, the other two opposite side walls of the composite block being inclined inwardly to the meeting faces of the sections to form a channel for engagement with the side links respectively, the composite block having a central transverse aperture, a bolt projecting through said aperture to draw the sections together under compression against the said four engaged walls of the shackle, said sections being extended outwardly around the bolt, that will serve to compress the block sections against all said engaged members.

6. The combination with a spring shackle formed of side links that connect and support upper and lower sleeve members by bolts, of a composite block of rubber compressed between said two pairs of opposed members on its four outer walls respectively, the block being formed of two complementary sections in engagement on the plane of the sleeve bolts, the composite block being provided with a channel on each of two opposite sides to engage the said sleeves respectively, the other two opposite side walls of the composite block being inclined inwardly to the meeting faces of the sections to form a channel for engagement with the side links respectively, the composite block having a central transverse aperture, a bolt projecting through said aperture to draw the sections together under compression against the said four engaged walls of the shackle, said block inclined faces being spaced apart a greater distance than the distance apart of the links, said sections being extended outwardly around the bolt to compress the sections against all engaged members.

Signed at New York, N. Y., on this 10th day of March, 1928.

HENRY E. BLOMGREN.
